UNITED STATES PATENT OFFICE.

CHARLES F. MILLER, OF CRESCO, IOWA.

TRACE-CARRIER.

SPECIFICATION forming part of Letters Patent No. 287,456, dated October 30, 1883.

Application filed August 25, 1883. (No model.)

To all whom it may concern:

Be it known that I, CHARLES F. MILLER, a citizen of the United States, residing at Cresco, in the county of Howard and State of Iowa, have invented certain new and useful Improvements in Trace-Carriers, of which the following is a specification, reference being had therein to the accompanying drawings.

My invention relates to trace-supporters; and it consists in a metal support of a peculiar construction, as will be hereinafter more fully described in the specification and pointed out in the accompanying drawings, in which—

15 Figure 1 is a perspective view of a harness-trace and the supporter, and Fig. 2 a detail view of the supporter.

The object of the device is to furnish an adjustable carrier that will not permit the trace to fall or sag, and that will not quickly wear out.

In the ordinary way of carrying traces with hip-straps, the strap goes around the trace with two slide-loops and one buckle. There are usually four side straps to a set of harness, and as these are subjected to unusual wear, they do not last long. Again, metal trace-carriers have been made with a tongue secured to the loop by a spiral spring and bolt. They have also been made with a set-screw bearing against a plate, which in turn bears against the trace. These are more or less complex and expensive in manufacture, and as these various springs, set-screws, and plates are subjected to the action of the weather, they become rusted, dirty, and difficult to manipulate. These objections I have endeavored to remove by my improved supporter.

Referring more particularly to the drawings, 40 A represents the supporting-loop, the sides narrowing from the bottom to the top, and terminating in a central projection, a, to which is pivotally secured a hip-strap fastener, B. This fastener is provided with two lugs, b, a

cross-bar, b', and angular pin b². A rivet 45 passes through the lugs b and projection a, so that the carrier can have a side motion with the trace c, thereby removing strain upon the harness.

The loop or frame A is made of any suitable 50 metal, as is the strap-fastener B. The pin b² and bar b' prevent the strap D from slipping when once adjusted. I may, and preferably do, insert a roller, r, in the bottom of the loop, so that the trace can move therein without 55 friction. The sides of the loop are purposely narrowed from the bottom to the top, in order to give a broad bearing at the bottom and be contracted at the top, which reduces the size of the projection a and the weight of metal 60 in the loop. The support can be raised up or down on strap D.

I find that in using a trace-support of this kind I save about forty inches of leather, four buckles, and eight slide-loops, besides the time 65 and labor involved in the making of the slide-loops.

I am aware that trace-carriers have been made with hinged sides secured together by a set-screw. I am also aware of carriers having 70 been made with a loop and hinged side or tongue held in place by a bolt moved by a spiral spring. Such forms of construction I do not claim.

Having thus described my invention, what I 75 claim is—

A trace-supporter consisting of the metallic loop A, having the inclined sides and top projection, a, in combination with the strap-carrier B, having the lugs b, pivoted to the 80 projection a, substantially in the manner and for the purpose set forth.

In testimony whereof I affix my signature in presence of two witnesses.

CHARLES F. MILLER.
